INVENTOR

Elkanor Omensetter

United States Patent Office.

ELHANAN OMENSETTER, OF PHILADELPHIA, PENNSYLVANIA, ASSIGNOR
TO SAMUEL MACFERRAN, OF SAME PLACE.

Design No. 4,189, dated June 28, 1870.

DESIGN FOR IRON RAILING.

The Schedule referred to in these Letters Patent and making part of the same.

I, ELHANAN OMENSETTER, of the city of Philadelphia and State of Pennsylvania, have invented and produced a new and original Design for Iron Railing, of which the following is a specification.

The nature of my design is fully represented in the accompanying photographic illustration, to which reference is made.

The photograph represents a side elevation of a panel of a fence, composed of longitudinal rails A A' and open pales B.

The rails A A' have tenons, b, for connecting the same with the posts of the fence.

The middle portions of the pales B have a central ornament, e, from which radiate four straight rods, f.

Projecting each way, in a horizontal direction from the said central ornament, are ornaments g.

The end-portions h h of the pale B, which connect with the radiate rods f and rails A A', are open scroll and leaf-work.

The leaves j j run in the direction of the rails A A', and cover a portion of the same.

The rails A A' have ornamental bands, k, at their ends, and between the pales B.

I claim as my invention—

The design for iron railing, as shown.

In testimony that the above is my invention I have hereunto set my hand and affixed my seal this 23d day of April, 1870.

ELHANAN OMENSETTER. [L. S.]
